UNITED STATES PATENT OFFICE.

BEVERLY WHITE, OF CHICAGO, ILLINOIS, ASSIGNOR OF ONE-HALF TO ANTHONY YBANEZ, OF SAVANNAH, GEORGIA.

TYPEWRITER ATTACHMENT.

Application filed August 31, 1925. Serial No. 53,625.

My invention relates to improvements in typewriter attachments, and it consists in the combinations, constructions, and arrangements herein described and claimed.

5 In placing typewriter ribbons on the ribbon reels on the ordinary typewriter, one almost invariably gets his fingers soiled with ink, due to the fact that in order to get the hook through the ribbon to hold it, pressure 10 must be applied which forces the ink out on the fingers.

An object of my invention is to provide 15 means whereby the ribbon may be firmly secured to the reel and wound thereon without any liability of soiling the fingers from the ink of the ribbon.

A further object of my invention is to provide a device of the type described which 20 will permit the ribbon to be rolled on the ribbon reel in the ordinary manner.

A further object is to provide a holding 25 device for the ribbon which may be readily removed when desired, and which may be used in connection with another reel.

Other objects and advantages will appear 30 in the following specification, and the novel features of the invention will be particularly pointed out in the appended claims.

My invention is illustrated in the accompanying drawings, forming part of this application, in which—

Figure 1 is a plan view of a ribbon reel with my attachment applied thereto,

Figure 2 is a horizontal sectional view 35 along the line 2—2 of Figure 3, showing the ribbon holding device on the reel,

Figure 3 is a section along the line 3—3 of Figure 1, and

Figure 4 is a perspective view of the ribbon holding attachment.

In carrying out my invention, I provide the device shown in Figure 4. This consists of side members 1 and 2, and an intermediate integral curved member 3 connecting the two side members.

The member 3 is curved, as will be seen from the drawing, this curvature being concentric with that of the hub 4 of the ribbon reel 5. The side members 1 and 2 are preferably of such a width that the member 3 will frictionally hold the end of the ribbon against the hub 4 for a considerable portion of the periphery of the hub.

As will be seen from Figure 3, the members 1 and 2 are arranged to frictionally

engage the sides of the reel 5, but to extend slightly beyond the edge of the reel, as shown at 6. The attachment may be made in the form of a stamping or a casting, or in any form in which the sides engage the 60 sides of the reel, and the central portion 3 frictionally holds the end of the ribbon. In some instances, I prefer to make the sides 1 and 2 of spring metal, while in other instances they may be rigid, and the frictional contact with the sides of the reel may depend upon the spring in the reel itself, these reels being ordinarily made of thin sheet metal.

From the foregoing description of the 70 various parts of the device, the operation thereof may be readily understood. When it is desired to place a ribbon on the reel, it is only necessary to lay one end 7 of the ribbon (see Figure 2) on the hub 4, and then 75 force the attachment in between the side walls of the reel, so that the central portion 3 frictionally engages the ribbon, while the sides 1 and 2 engage the side walls of the reel. A ribbon may now be wound on 80 the reel and will enter between the side walls 1 and 2, as shown in Figure 2. In this figure, it will be observed that the second convolution passes over the member 3. The view is exaggerated for the purposes 85 of illustration. As a matter of fact, the ribbon will lie close to the first convolution. As will be seen from Figure 1, the portion 90 90 projects beyond the periphery of the reel 5. When it is desired to remove the attachment, the portion 6 may be gripped by the fingers and the attachment may be removed by pulling it out from between the side walls of the reel. In the operation of applying or removing the device there is 95 no liability of getting the fingers soiled from the ink.

Since the attachment is made in the standard sizes, it may be used in connection with different reels, and when in position permits the use of the reel in the ordinary manner.

I claim:

1. The combination with a typewriter ribbon reel having a hub, of a typewriter ribbon clamping device comprising a central arc-shaped member curved to conform with the contour of the hub and having an unbroken concave surface and an unbroken convex surface, and integral sides at the end 100 105 110

of said central member, the interior and exterior portions of the sides being unbroken, and the outer portion of said sides being arranged to frictionally engage the side walls of the reel.

- 5 2. The combination with a typewriter ribbon reel having a hub, of a typewriter ribbon clamping device comprising a central arc-shaped member curved to conform with
10 the contour of the hub and having an unbroken concave surface and an unbroken convex surface, and integral sides at the end of said central member, the interior and exterior portions of the sides being unbroken,
15 and the outer portion of said sides being

arranged to frictionally engage the side walls of the reel, said sides having a portion extending slightly beyond the outer edge of said side walls.

3. As an article of manufacture, a ribbon clamping device for typewriters, comprising a central arc-shaped member having an unbroken surface on its concave and convex surfaces, and integral side members comprising flat plates extending in planes at 20 right angles to the axis of said arc-shaped member at the ends thereof, on the convex side of each arc-shaped member.

BEVERLY WHITE.
